SAMUEL PESKIND, OF CLEVELAND, OHIO.

LOCKING APPARATUS FOR VACUUM FUEL SYSTEM.

1,316,592.

Specification of Letters Patent. Patented Sept. 23, 1919.

Application filed June 4, 1919. Serial No. 301,754.

To all whom it may concern:

Be it known that I, SAMUEL PESKIND, a citizen of the United States, and a resident of Cleveland, county of Cuyahoga, and State of Ohio, have invented a new and useful Improvement in Locking Apparatus for Vacuum Fuel Systems, of which the following is a specification, the principle of the invention being herein explained and the best mode in which I have contemplated applying that principle, so as to distinguish it from other inventions.

The subject of the present invention is the provision of locking means suitable for use with vacuum fuel systems, such as are commonly employed on automobiles. The device consists of means for releasing the vacuum on the small tank and of other means for locking the fuel lines preventing flow of gasoline from the vacuum tank to the carbureter. To the accomplishment of the foregoing and related ends, said invention, then, consists of the means herein-after fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings:—

Figure 1 is a diagrammatic layout of the device with parts in section, showing it connected to a vacuum system; Fig. 2 is a section through the vacuum line lock; Fig. 3 is a similar section but showing the lock in a second position; Fig. 4 is a section on the line 4—4, Fig. 2; and Figs. 5 and 6 are diagrammatic layouts of modified forms of the device.

The present invention consists of a suitable lock 1 which consists of a casing 2 having a key actuated valve 3, the casing being shown as mounted in the cowl board 4 of a vehicle. The valve 3 is provided with an aperture 5 adapted to register with two ports 6 and 7 in the casing, and the valve also has two cutaway portions 8 which are connected to a conduit 9 in the bottom of the valve casing, the conduit exhausting to the atmosphere through a series of apertures 10 as best shown in Fig. 3.

The usual suction line 11 of a vacuum system is connected to the engine manifold 12 and then leads to one port 6 of the lock,

the opposite port 7 being in communication through a pipe 13 to a second valve casing 14. This valve casing is shown as mounted on the dash board 15 of the vehicle and has a piston valve 16 mounted therein. The suction line 13 enters the top of the casing and by means of a by-pass 17 is connected to an outlet port 18 which is in turn in communication with the vacuum tank 19 through the line 20.

At the middle of the casing, the main gasoline feed line 21 is connected and is, in the normal position of the valve, open to a fuel line 22 leading to the vacuum tank. The fuel line 23 from the lower part of the vacuum tank is connected to the bottom portion of the valve casing and leads out through a pipe 24 to the carbureter. A vent port 30 allows the gasoline to return to the vacuum tank so that the piston valve may close.

Within the casing as before mentioned is a piston valve 16 formed with three full-sized portions 25, 26 and 27, connected by smaller portions 28, the lowest portion 27 having a cone shaped valve 29 closing the outlet pipe 24 when the valve is in its down position. In the normal running position shown in Fig. 1, the suction line 13 by-passes around the upper valve part 25 and then leads to the vacuum tank. The gasoline from the main tank passes below the intermediate valve part 26 and out to the vacuum tank. The carbureter fuel line passes below the lower valve part 27 and out through the line 24 to the carbureter.

The piston valve is automatic in its operation. When the valve drops, all the ports are closed and the suction created at the top of the casing raises the valve and allows the suction line to be opened to the vacuum tank thus drawing the gasoline into the same from the main tank.

When it is desired to lock the car, the key lock is turned to the position shown in Fig. 3 venting the incoming suction line 6 and also the outgoing suction line 7 leading to the valve casing through the apertures 10. This allows the piston valve to drop, which closes the main gasoline line to the vacuum tank, as well as the line from the vacuum tank to the carbureter. As no suction can be placed on the valve casing, the piston valve will remain in this position until the key valve is again turned to the position

shown in Fig. 2, when the suction line is closed through the key valve to the valve casing, raising the piston valve and operating the vacuum tank again.

5 In Fig. 5 I have shown a modified construction, the manifold 31, carbureter 32, carbureter line 33, and main gasoline line 44 and vacuum line 34 being of the usual construction. Here the two devices are incorporated in a single casing 35 carrying the vacuum tank 36 and the valve casing 37. A one-way lock 38, controlled by a key, is used, there being a T-joint 39 in the vacuum line, one branch 40 leading to the tank, and the other branch 41 leading to the lock. The valve casing is connected through the lock to the vacuum line and the piston valve has two portions 42 and 43 controlling the main gasoline line 44 and the carbureter line 33, respectively.

25 In this form, while the engine is running, the lock 38 is closed and the piston valve is in its lower position due to its weight, allowing the gasoline to flow through both the main gasoline line and the carbureter line. When the lock is turned opening the vacuum line to the valve casing the vacuum in the casing raises the piston valve, closing both the main gasoline line and the line to the carbureter. Any attempt to run the engine closes these two lines and thus no gasoline can reach the carbureter.

30 In Fig. 6 a form similar to Fig. 5, but with a slight modification, is shown. In this form the lock is a three-way lock, the vacuum line 50 entering one side, and, in the normal running position, being connected to the vacuum tank through the line 51. In the locked position the line 51 is vented to the atmosphere through the lock and the line 50 is connected to the valve casing through the pipe 52, thus raising the plunger and closing the gasoline line and the carbureter line, preventing the flow of gasoline.

45 In apparatus of the present type, where the vacuum tank is already installed, the present device may be readily added, while it is, of course, understood that in new installations, it would be preferable to incorporate the locking means directly with the vacuum tank. The key lock may be placed in any readily accessible position, but having the apertures 10 to the atmosphere placed in such a position that they are relatively 50 inaccessible to prevent plugging the same. As the vacuum line controls the piston valve, the latter operates automatically to close the gasoline lines upon movement of the key.

60 By the use of the present apparatus any gasoline system may be securely locked and a carbureter may be shut off from the gasoline supply. In any fuel system where a carbureter supply line or main gasoline line is used, the line is controlled by the valve 65 actuated by the vacuum line. The lock con-

trols the vacuum line so that the valve closes the fuel line ports in the casing. When the car is stopped the engine may run until the fuel in the carbureter is exhausted, after which the car cannot be started until the lock 70 is turned to open the valve. The car, of course, may be stopped, the engine shut off and the device locked without exhausting the fuel in the carbureter. In this case the car can be started but can only run the 75 short distance necessary to exhaust the fuel in the carbureter before the engine stops and becomes impossible to start.

80 Other modes of applying the principle of my invention may be employed instead of the one explained, change being made as regards the mechanism herein disclosed, provided the means stated by any of the following claims or the equivalent of such stated means be employed.

85 I therefore particularly point out and distinctly claim as my invention:—

1. In locking apparatus of the character described, the combination with a main gasoline line, a vacuum tank, a vacuum line and a carbureter fuel line, of a lock connected in said vacuum line and adapted to open same to the atmosphere in one position, and a valve casing connected in said vacuum line, and a piston valve in said casing movable under such vacuum and adapted to close said vacuum line to said vacuum tank upon opening of said vacuum line to the atmosphere.

2. In locking apparatus of the character described, the combination with a main gasoline line, a vacuum tank, a vacuum line and a carbureter fuel line, of a lock connected in said vacuum line and adapted to open same to the atmosphere in one position, and a valve casing connected in said vacuum line 100 and to said carbureter line, a piston valve in said casing movable under such vacuum and adapted to close said vacuum line to said vacuum tank and said carbureter fuel line upon movement of said lock in opening said 105 vacuum line to the atmosphere.

3. In locking apparatus of the character described, the combination with a main gasoline line, a vacuum tank, a vacuum line and a carbureter fuel line, of a lock connected in said vacuum line and adapted to open same to the atmosphere in one position, and a valve casing connected in said vacuum line in said main fuel line and in the carbureter fuel line, a three part 115 piston valve in said valve casing adapted to move upon opening of said vacuum line to the atmosphere to close said vacuum line and said main gasoline line to said vacuum tank and said carbureter line.

4. In locking apparatus of the character described the combination of a vacuum line and a gasoline line, a valve casing having openings adapted to be connected to said vacuum line and in said gasoline line, a pis- 120 125 130

- ton-valve mounted in said casing and adapted to control such openings in said gasolene line, movement of said valve being controlled by said vacuum line, and a lock in said vacuum line adapted to control the vacuum in said casing to operate said valve. 40
5. In locking apparatus of the character described the combination of a vacuum line, a carbureter fuel line, a valve casing having openings adapted to be connected to said vacuum line and in said carbureter fuel line, a piston valve mounted in said casing and adapted to control such openings in said gasolene line movement of said valve being controlled by said vacuum line, and a lock in said vacuum line adapted to control the vacuum in said casing to operate said valve. 45
10. In locking apparatus of the character described, the combination of a valve casing provided with a series of inlet and outlet openings for a vacuum line, a main line and carbureter fuel lines, respectively, a piston valve movably mounted in said casing and adapted in one position to open said vacuum, main fuel and carbureter lines through said casing, said valve being operated by the negative pressure in said vacuum line to vent the same to the atmosphere to move said valve to its closed position. 50
15. In apparatus of the character described, the combination with a vacuum line, a main fuel line, a vacuum tank and a carbureter line, of a valve casing connected to said vacuum line, said gasolene line and said carbureter line, ports in said casing connecting said gasolene line and said carbureter line, a piston valve in said casing adapted in one position to close said ports, said valve being operable by the vacuum in said casing, and locking means in said vacuum line adapted to control the vacuum in said casing to operate said valve. 55
20. In apparatus of the character described, the combination with a vacuum line, a main fuel line, a vacuum tank and a carbureter line, of a valve casing connected to said vacuum line, said gasolene line and said carbureter line, ports in said casing connecting said gasolene line and said carbureter line, a piston valve in said casing adapted in one position to close said ports, said valve being operable by the vacuum in said casing, valve means in said vacuum line for controlling the vacuum in said casing to move said piston, and means adapted to lock said valve means in desired position. 60
25. 7. In apparatus of the character described, the combination with a vacuum line, a main fuel line, a vacuum tank and a carbureter line, of a valve casing connected to said vacuum line, said gasolene line and said carbureter line, a piston valve in said casing
30. 8. In apparatus of the character described, the combination with a vacuum line, a main fuel line, a vacuum tank and a carbureter line, of a valve casing connected to said vacuum line, said gasolene line and said carbureter line, ports in said casing connecting said gasolene line and said carbureter line, a piston valve in said casing adapted in one position to close said ports, said valve being operable by the vacuum in said casing, valve means in said vacuum line for controlling the vacuum in said casing to move said piston, and means adapted to lock said valve means in desired position. 65
- 35.

Signed by me, this 22 day of May, 1919.

SAMUEL PESKIND.
